(57) **CLAIM**

The ornamental design for a vehicle occupant monitor, as shown and described.

DESCRIPTION

FIG. 1 is a front perspective view of a vehicle occupant monitor, showing my new design.

FIG. 2 is a front elevation view of the vehicle occupant monitor shown in FIG. 1.

FIG. 3 is a rear elevation view of the vehicle occupant monitor shown in FIG. 1.

FIG. 4 is a right side view of the vehicle occupant monitor shown in FIG. 1.

FIG. 5 is a left side view of the vehicle occupant monitor shown in FIG. 1.

FIG. 6 is a top plan view of the vehicle occupant monitor shown in FIG. 1; and,

FIG. 7 is a bottom plan view of the vehicle occupant monitor shown in FIG. 1.

The broken lines in the above-described figures illustrate various rotatable portions of a steering wheel assembly to which the vehicle occupant monitor system is coupled. The broken lines are provided for illustrative purposes only and form no part of the claimed design.
